UNITED STATES PATENT OFFICE.

BENEDICT T. GIBBS, JR., OF CHICAGO HEIGHTS, ILLINOIS, ASSIGNOR TO MORDEN FROG & CROSSING WORKS, OF CHICAGO, ILLINOIS, A CORPORATION OF ILLINOIS.

ADJUSTABLE ANCHOR BLOCK FOR SLIP SWITCHES.

Application filed July 31, 1924. Serial No. 729,399.

To all whom it may concern:

Be it known that I, BENEDICT T. GIBBS, Jr., a citizen of the United States, residing at Chicago Heights, in the county of Cook 5 and State of Illinois, have invented a certain new and useful Improvement in Adjustable Anchor Blocks for Slip Switches, of which the following is a specification.

This invention relates to anchor blocks 10 for positively securing adjacent, spaced, movable track parts in predetermined position with reference to each other. It is especially applicable to the movable joints of switch points in slip switches where it is 15 necessary that all the track parts be constantly maintained in proper relation to each other, notwithstanding heavy wear constantly taking place.

The object of the invention is to provide 20 an anchor block which is itself internally adjustable to correct errors in adjacent track, and to keep the proper gauge and alignment of said track at all times, as well as a mechanically tight joint of said movable parts 25 when greatly worn from excessive use.

The invention consists of means for attaining the foregoing and other objects, which can be easily and comparatively cheaply made, which is satisfactory in use 30 and is not readily liable to get out of order. More particularly, the invention consists in numerous features and details of construction which will be hereafter more fully set forth in the specification and claims.

Referring to the drawings in which like numerals refer to the same parts throughout the several views:

Figure 1 is a plan view of a conventional, complicated railroad crossing, technically 40 known as a slip-switch, to which this invention may be applied with satisfactory results.

Figure 2 is an enlarged, plan view of the block of this invention.

Figure 3 is a sectional view on the line 3—3 of Figure 2.

Figure 4 is a perspective view of an adjusting wedge.

Figure 5 is a still more enlarged plan 50 view, on the line 5—5 of Figure 6, of the block of this invention.

Figure 6 is a longitudinal, sectional view on the line 6—6 of Figure 5.

Figure 7 is a sectional end view on the irregular line 7—7 of Figure 5.

In the conventional crossing or slip switch of Figure 1, 16 and 18 are respectively the curved stock-rails connected, respectively, at their outer ends to the outer main rails 20 and 22 of the railroad tracks A B and C D, which cross each other at the center of the figure. Inside of these curved stockrails are bent connecting rails 23 and 24 to whose ends are pivoted switchpoints 25, 26, 27 and 28. Inside of the bent connecting rails are 60 straight connecting rails 31, 32, 33 and 34, connecting at their outer ends (beyond the figure) to an ordinary frog, which is in turn connected to the inner rails of the main tracks, referred to. On the inner ends of 70 these straight connecting rails 31, 32, 33 and 34 are pivoted movable switch-points 35, 36, 37 and 38. Inside of the mechanism just described are the curved connecting rails 40 and 42 having pivoted to their ends switch points 43—44—45 and 46. The switch-points 25 and 44 are connected together by switch rod 48, which permits of their being moved together. In a similar manner switch-points 43 and 26 are connected by switch rod 50, switch-points 27 and 46 by switch-rod 52 and switch-points 45 and 28 by switch-rod 54.

In the crossing at the points indicated in Figure 1 are four anchor blocks of this invention, 56—57—58 and 59. These blocks are identical in construction and therefore only one, specifically block 58, will be described.

In normal use, block 58 performs the function of anchoring track members 23—27 to track members 33—37. It is made up of two substantially identical U-shaped sections 62 and 64 placed with their faces 96 and 110 against the respective rail parts just named, the upper or free ends of the U members 90 being pointed toward each other as shown with wedge 66 between one pair of U arms of members 62 and 64 and wedge 68 between the other opposed pair of U arms. The wedges are provided with elongated slots 70 through which pass bolts 72 or 74, as the case may be, on which the wedges slide along 100

the inclined surfaces 74 on the adjacent free **U** arm ends of blocks 62 and 64. Bolts 72 detachably connect, through the wedge 68, one pair of such opposed **U** arms and bolts 74 similarly connect the opposite pair of arms through wedge 66.

Wedges 66 and 68 are preferably but not necessarily pointed toward each other so that as either wedge is driven in between 10 block sections 62 and 64 to widen the space between the track parts, the wedge noses 78 and 80 project more and more into the open space 82 at the center of the block and lock pins 84 and 86 can be inserted in selected 15 available holes 88 and 90 in the respective wedges with the pins 84 and 86 bearing against opposite walls 92 and 94 of the opening 82.

Face 96 of block section 62 carries bolts 20 98 which pass through track parts 16 and 23 and one end spacing block 100 to hold these parts together as shown and, similarly, bolts 102 connect flange 96, track parts 20 and 27 and the intervening part of block 100. To 25 facilitate the normal swinging movement of switch point 27, a thimble 106 (Fig. 6) is provided on at least one bolt 102 and a clearance space 108 is provided as shown in Figure 6 between flange 96 and switch point 27. 30 In similar manner, block section 64 is provided with a face flange 110 connected by bolts 112 to track parts 37 and 40 and one end of spacing block 114. Likewise, bolts 116, connect flange 110, track parts 33 and 35 45 and the opposite end of spacing block 114.

In operation, a block, as 58, is assembled 40 in track as shown, the wedges 66 and 68 being adjusted to bring the track parts connected to that particular block into normal usable position. When wear takes place, thus making the crossing loose and out of alignment, bolts 72 and 74 are loosened enough so wedges 66 and 68 can be driven to new positions which will properly adjust the 45 track parts on opposite sides of the block with reference to each other, whereupon, the bolts 72 and 74 are tightened and the pins 84 and 86 are placed in proper new holes 90 and 88, whereupon the track parts controlled by the particular block are again 50 ready for safe, normal use.

Having thus described my invention, what I claim as new and desire to secure by Letters Patent is:

55 1. As an article of manufacture, a track anchor block made in two separate sections, adjacent each other, means for securing track parts to opposite edges of the block and means between the block parts detachably adjusting said block parts to selectively control the distance between the track carrying 60 edges of the block.

65 2. As an article of manufacture, a track anchor block made in two separate sections, adjacent each other, means for securing

track parts to opposite edges of the block and a wedge between the block parts detachably adjusting said block parts to selectively control the distance between the track carrying edges of the block. 70

3. As an article of manufacture, a track anchor block made in two separate sections, adjacent each other, means for securing track parts to opposite edges of the block and a pair of wedges between the block parts detachably adjusting said block parts to selectively control the distance between the track carrying edges of the block. 75

4. As an article of manufacture, a track anchor block made in two separate sections 80 adjacent each other, means for securing track parts to opposite edges of the block and a pair of wedges pointed toward each other between the block parts detachably adjusting said block parts to selectively control the distance between the track carrying 85 edges of the block.

5. As an article of manufacture, a track anchor block made in two separate sections, adjacent each other, means for securing 90 track parts to opposite edges of the block, and a wedge between the block parts detachably adjusting said block parts to selectively control the distance between the track carrying edges of the block, the wedge being provided with elongated slot and bolt connection between opposite block sections. 95

6. As an article of manufacture, a track anchor block made in two separate sections, adjacent each other, means for securing track parts to opposite edges of the block and a pair of wedges between the block parts detachably adjusting said block parts to selectively control the distance between the track carrying edges of the block, the wedges being provided with elongated slot and bolt connection between opposite block sections. 100

7. As an article or manufacture, a track anchor block made in two separate sections adjacent each other, means for securing track parts to opposite edges of the block and a pair of wedges pointed toward each other between the block parts detachably adjusting said block parts to selectively control the distance between the track carrying edges of the block, the wedges being provided with elongated slot and bolt connection between opposite block sections. 110

8. As an article of manufacture, a track anchor block made in two separate sections, adjacent each other, means for securing track parts to opposite edges of the block, a wedge between the block parts detachably adjusting said block parts to selectively control the distance between the track carrying edges of the block, and a transversely movable pin selectively locking the wedge against longitudinal movement. 120

9. As an article of manufacture, a track anchor block made in two separate sections, 130

adjacent each other, means for securing track parts to opposite edges of the block, a wedge between the block parts detachably adjusting said block parts to selectively control the distance between the track carrying edges of the block, the wedge being provided with elongated slot and bolt connec-

tion between opposite block sections, and a transversely movable pin selectively locking the wedge against longitudinal movement. 10

In witness whereof, I have hereunto subscribed my name.

BENEDICT T. GIBBS, JR.
